(57) **CLAIM**

The ornamental design for a multi-lobe sensor, as shown and described.

DESCRIPTION

FIG. 1 is a top front perspective view of an embodiment of a multi-lobe sensor;

FIG. 2 is a bottom rear perspective view of the multi-lobe sensor of FIG. 1;

FIG. 3 is a top view of the multi-lobe sensor of FIG. 1;

FIG. 4 is a bottom view of the multi-lobe sensor of FIG. 1;

FIG. 5 is a rear view of the multi-lobe sensor of FIG. 1;

FIG. 6 is a front view of the multi-lobe sensor of FIG. 1;

FIG. 7 is a right side view of the multi-lobe sensor of FIG. 1; and,

FIG. 8 is a left side view of the multi-lobe sensor of FIG. 1.

The broken lines are shown for the purpose of illustrating parts of the article that form no part of the claimed design.

1 Claim, 6 Drawing Sheets
